UNITED STATES PATENT OFFICE.

HARRY E. NORVIEL, OF ANDERSON, INDIANA, ASSIGNOR TO GENERAL MOTORS CORPORATION, A CORPORATION OF DELAWARE.

SWITCH.

Application filed February 11, 1922. Serial No. 535,920.

To all whom it may concern:

Be it known that I, HARRY E. NORVIEL, a citizen of the United States of America, residing at Anderson, county of Madison, 5 State of Indiana, have invented certain new and useful Improvements in Switches, of which the following is a full, clear, and exact description.

This invention relates to electrical switches 10 and particularly to that type of switch which is adapted for use on the instrument board of an automobile.

The present invention includes improvements on the electric switch shown in my 15 copending application Serial No. 481,138, filed June 28, 1921, in which application is disclosed a switch having a glass cover for the switch dial, through which extend switch controlling members such as switch levers 20 and a lock member for locking one or more of the switch members in position.

It is one of the objects of the present invention to prevent dirt or other foreign matter from entering between the dial and 25 cover which would tend to obscure the lettering on the dial and also detract from the appearance of the switch.

Other and further objects of the present invention will be apparent from the following description, reference being had to the 30 accompanying drawings, wherein a preferred embodiment of the present invention is clearly shown.

In the drawings:

35 Fig. 1 is a front view of a switch embodying the present invention;

Fig. 2 is a side view thereof;

Fig. 3 is a front view of an assembly 40 of a switch dial and dial cover;

Fig. 4 is a sectional view taken substantially on the line 4—4 of Fig. 1, certain parts being omitted for the sake of clearness; and

Fig. 5 is a fragmentary rear view of the switch looking in the direction of the arrow 45 5 of Fig. 2.

In the drawings, a switch case 20 includes a substantially cylindrical side wall 21 and a front wall 22 which is apertured to provide for the extension thereinto of a num-

ber of switch controlling elements such as 50 a pair of switch shafts 23 each of which is operated by a lever 24, and a lock member 25 of the Yale type. Lock member 25 is preferably provided with one or more lugs 55 26 which may be secured to the case 20 in any convenient manner as by means of screws 27, one being shown in Fig. 4. Each shaft 23 carries a multiple contact element 28 provided with a plurality of contact arms 29, one of these arms being shown in 60 Fig. 4. Member 29 cooperates with a plurality of stationary contacts, not shown, and these contacts are suitably mounted in a switch back plate carrying a plurality of terminals 30 which are connected to the various stationary contacts of the switch in any suitable manner to effect the desired circuit connections. As the exact nature 65 of the switch does not of itself form a part of the present invention, further disclosure 70 thereof is thought to be unnecessary. The exact nature of the switch contact members is more particularly described and claimed in my copending application referred to.

The switch case 20 is provided with an 75 annular flange 31 which is substantially circular in contour and forms a part of the front face of the switch case, and adjacent this flange 31 is located a ring 32 of relatively soft material such as paper. Next to 80 the ring 32 is located a switch dial 33 and next to the dial 33 is located the dial cover 34 of transparent material, preferably glass. Dial 33 and cover 34 are provided with aligned holes for the projection there- 85 through of the switch controlling members 23 and 25. In Fig. 3, 35 indicates the aligned holes through the dial and cover for the lock 25 and the numerals 36 indicate the aligned holes through the dial and cover 90 for the switch shafts 23 respectively. By referring to Fig. 4 it will be noted that the main body portion of the dial 33 presses against the packing ring 32 but is spaced 95 from the cover 34. The dial 33 is provided with an annular edge flange 37 and with annular flanges 38 and 39 adjacent the holes 35 and 36. These flanges 37, 38, and 39 ex-

tend the same distance from the body portion of the dial 33 and on the same side thereof so that in assembled position these flanges 37, 38, and 39 may press against the transparent cover 34.

The dial 33 and the cover 34 are secured together adjacent the holes 35 and 36 by means of sleeves 40 and 41, respectively. The sleeve 40 extends through the hole 35 and is provided with a flange 42 bearing against the outer face of the cover 34 and with a flange 43 which is bent over or spun over the rear side of the flange 38 of dial 33. After the dial 33, cover 34, and sleeve 40 have been assembled, a sleeve 41 extends through each of the holes 36, and each sleeve 41 is provided with a previously formed annular flange 44 which fits within and bears against a recess 45 provided in the cover 34. After the members 33, 34, and 41 have been assembled, the rear edge of the sleeve 41 is bent over or spun over to provide a flange 46 bearing against the rear edge of the flange 39.

25 The body portion of the dial 33 is held against the ring 32 and the flange 37 of dial 33 is held against the cover 34 by means of bezel ring 50 having a flange 51 bearing against the beveled edge 52 of the cover 34, 30 and having a plurality of ears 53 each of which is bent over and into a notch 54 provided on the rear face of the flange 31 of case 20. Before bending these ears over they project rearward from the ring 50 as indicated at 53^a in Fig. 2.

It is apparent from the foregoing that a space has been provided between the main body of the dial 33 and the cover 34 to permit raised lettering being placed on the dial 33 without the lettering coming in contact with the back of the cover 34. This space between the dial and cover is effectively sealed in the manner described. It is very important to provide an effective seal between the dial and the cover in order that the lettering on the dial may not become obscure and in order that the appearance of the switch face may not be spoiled by any dirt or foreign matter becoming deposited on the face of the dial. The switch cover 34 is preferably constructed of molded glass having its face ground and burred to present a handsome appearance and it is apparent that simply by keeping the front of the glass cover clean the good appearance of the switch may be maintained and the dial will be clearly visible since the possibility of dirt entering between the dial and cover has been substantially eliminated.

60 While the form of mechanism herein shown and described constitutes a preferred form of embodiment of the invention, it is to be understood that other forms might be adopted, all coming within the scope of 65 the claims which follow.

What I claim is as follows:

1. In a switch, the combination with a switch case, a dial and a transparent dial cover spaced apart and having aligned openings, and switch controlling members extending through said openings and into said case; of means for sealing together said dial and dial cover around said openings; and means for securing said dial and cover to said case. 70

2. In a switch, the combination with a switch case, a dial and a transparent dial cover spaced apart and having aligned openings, and switch controlling members extending through said openings and into said case; of means for sealing said dial to said dial cover around the openings; and means for sealing said dial to said dial cover at the outer edges thereof. 80

3. In a switch, the combination with a switch case, a dial and a dial cover spaced apart over the greater portion of their areas and having aligned openings, and switch controlling members extending through said openings and into said case; of means for holding said dial and said dial cover in engagement adjacent the openings; and means for holding said dial and dial cover in engagement at the outer edges thereof, whereby the space between said dial and cover is substantially closed off. 90

4. In a switch, the combination with a switch case having openings through the front face thereof, and switch controlling members extending through said openings; of a dial having openings aligned with the openings in the case, said dial having flanges surrounding said openings and spaced from the main portion of the dial; a transparent dial cover having openings aligned with the openings in the dial; sleeves each extending into aligned openings in said dial and cover, and having end flanges bearing, respectively, against the front of the dial cover and against the back of said flanges of the dial; and means for securing the dial and cover to the casing. 100

5. In a switch, the combination with a switch case having openings through the front face thereof, and switch controlling members extending through said openings; of a dial having openings aligned with the openings in the case; a transparent dial cover having openings aligned with the openings in the dial; sleeves each extending into aligned openings in said dial and cover, and having end flanges bearing, respectively, against the front of the dial cover and against the back of the dial; and means for securing the dial and cover to the casing. 110

6. In a switch, the combination with a switch case; of a dial having an edge flange raised from the main portion thereof; a transparent dial cover; means for securing the dial and dial cover to the case with the 120

edge flange of the dial in engagement with the back of the dial cover; and a packing ring between the dial and the switch case.

7. In a switch, the combination with a switch case including a flange extending from the main body thereof; of a dial having an edge flange raised from the main portion thereof; a dial cover; a packing ring between the main portion of the dial and the case; and a bezel ring having a flange 10 bearing against the dial cover and having fingers bent over the case flange, whereby to secure the dial and cover to the case with the dial flange in engagement with the back of the dial cover. 15

In testimony whereof I hereto affix my signature.

HARRY E. NORVIEL.
